UNITED STATES PATENT OFFICE.

ERNEST A. LLEWELLYN, OF WILTON, MAINE, ASSIGNOR TO G. H. BASS & COMPANY,
OF WILTON, MAINE, A CORPORATION OF MAINE.

MOCCASIN.

1,410,105.

Specification of Letters Patent. Patented Mar. 21, 1922.

Application filed October 25, 1920. Serial No. 419,424.

To all whom it may concern:

Be it known that I, ERNEST A. LLEWELLYN, a citizen of the Dominion of Canada, and subject of the King of Great Britain and 5 Ireland, residing at Wilton, in the county of Franklin and State of Maine, have invented certain new and useful Improvements in Moccasins; and I do hereby declare the following to be a full, clear, and exact description of the invention, such as will enable others skilled in the art to which it appertains to make and use the same.

This invention relates to boots and shoes which are made usually of soft leather, and 15 more particularly to moccasins or the like.

The main objects of the invention are to provide a moccasin having a toe-piece made wide at the front and provided with a narrow tongue-like rear part which extends up 20 over the ball of the foot and is secured to the vamp or front upper part of the shoe by seams which extend near the medial line of the foot, on opposite sides of said line, while the widened front part is secured over 25 the toe portion of the shoe by a seam which extends in a continuous curve from a point at one side about the base of the large toe to a diametrically opposite point on the other side; the several parts of the shoe being 30 so formed and secured together by seams so arranged as to give increased strength where needed and secure ease and comfort to the wearer and reduce to a minimum the danger of ripping or being torn apart at the seams.

35 The invention will first be hereinafter more particularly described, with reference to the accompanying drawings, which form a part of this specification, and then pointed out in the claims at the end of the description.

In said drawings,

Fig. 1 is a perspective view of a preferred form of moccasin embodying my invention;

45 Fig. 2 is a perspective view of the same with the tongue and gussets removed, showing one of the quarters on the near side loosened and turned down and the narrow part of my improved toe-piece loose and 50 turned back over the toe of the shoe so as to more clearly illustrate the mode of connecting the several parts;

Fig. 3 is a detail sectional view taken on the line 3-3 of Fig. 1, looking toward the 55 toe;

Fig. 4 is a fragmentary detail view illustrating the tongue underlying the upper end of the toe-piece instead of overlying it as in Fig. 1;

Fig. 5 is a bottom plan view of the sole 60 portion of the moccasin;

Fig. 6 is a plan view of a blank from which the front part of the moccasin is formed;

Fig. 7 is a plan view of the toe-piece or 65 blank from which the toe-piece is formed;

Fig. 8 is a perspective view of a moccasin of the same type as that shown in Fig. 1, but having the rear portions of the front part of the shoe or vamp extended to the 70 heel of the shoe; and

Fig. 9 is a plan view of the blank from which the vamp or front part of the moccasin with rearward extensions shown in Fig. 8 is formed.

75 Referring to said drawings, in which the same reference letters are used to denote corresponding parts in different views, the front part of the shoe or moccasin, as shown in Fig. 1, is formed from a blank A, consisting of a single piece of leather having a centrally disposed V-cut therein or an approximately V-shaped portion cut-out, as at a, the front edge thereof being continuously curved from a point at one side nearly 80 midway of the blank to a diametrically opposite point on the other side, and also having on opposite sides thereof laterally projecting extensions or wings a¹, with straight edges, and rearwardly projecting portions 85 a², having curved edges; said blank being adapted to be bent on the lines x, Fig. 6, and given the form indicated in Fig. 1, and to have the edges of its central bifurcated or cutaway portion a secured together by 90 a seam extending along the medial line of the sole and its upturned side wings or extensions a¹, secured together along their edges by a seam which extends along a medial line over the ball of the foot, while 100 its upturned front curved edge, shaped to form an approximately U-shaped toe-portion, is secured to the front curved edge of a toe-piece B, by hand or machine seam; said toe-piece having a wide substantially 105 semi-circular front portion which is designed and adapted to cover a correspondingly shaped open space over the toes between the front edges of the side wings a¹ and the upturned front edge of the vamp. Said toe- 110

piece, as shown, is made wide at the front and its edges diverge to an intermediate point and then converge abruptly rearwardly until they merge in a narrow tongue-like portion *b* which extends from said wide front part rearwardly over the ball of the foot to a point about midway of or near the middle of the shoe. Said narrow tongue-like portion is secured to the underlying vamp or side wings *a*¹ of the said front part of the shoe by seams which extend longitudinally near the medial line of the foot on opposite sides of said line and widen or spread apart as they approach the widened front portion of the toe-piece. Preferably said side wings *a*¹ should be of sufficient length to permit their upturned outer edges to meet over the instep and be secured together by a seam extending longitudinally along the medial line of the foot, as shown in Fig. 2, but in some cases it may be desirable to shorten said side wings, and instead of securing them together along their meeting edges, to secure them to the toe-piece by seams which extend near the medial line of the foot on opposite sides of said line, thus separating the edges of said wings and leaving a space between said edges along said medial line. As shown, a tongue *D* is secured to the vamp by a transverse seam over the ball of the foot and lies preferably over the rear part of the toe-piece, as shown in Figs. 1 and 8, but may underlie said rear part of the toe-piece, as shown in Fig. 4, and may have secured thereto gussets *E*, the outer edges of which are secured to the quarters *F*, but the gussets are not essential and may be omitted. The toe-piece is secured to the vamp by a continuous seam extending across its upper end, joining it to the tongue, and thence downwardly along its edges on both sides near the medial line of the foot, and diverging near the front where the toe-piece begins to widen and continuing around the curved front which is usually secured to the vamp by a hand-seam.

The lower portion of the vamp might be made without a V-cut in its center, but such cut is preferable, to give a better fit. The rearwardly extending portions of the blank preferably terminate at the shank of the foot, as shown in Fig. 1, but such portions may run to the heel, as shown in Fig. 8.

In Figs 8 and 9 is shown a modification of my invention, wherein the blank *A*¹ has rearwardly extending portions *a*³ adapted to form the lower portion of the quarters and the rear part of the sole as well as the front part thereof, said rearwardly extending portions being secured together at the heel by a vertical seam. The upper portions of the quarters *F*¹ are each made from a blank, the lower edge of which is secured to the upper edge of the upturned outer por-

tions of the rearward extensions *a*³ of the blank *A*¹, which form the lower portions of the quarters, and the vertical seam which unites the rear edges of the quarters and also the rear ends of the rearwardly extending portions of the blank which form the lower portions of the quarters is covered by the usual back-stay *G*.

The upper end of the toe-piece *B*, as shown in Fig. 1, is round, while in Fig. 8, said end has a straight edge, and the seam which unites said end to the tongue *D*¹ extends straight across; otherwise the toe-piece and associated parts and the mode of connecting the same are the same as described with reference to Figs. 1 to 7 of the drawings.

Having thus described my invention, what I claim as new and desire to secure by Letters Patent of the United States is:

1. In a moccasin, a front part or vamp made from a blank consisting of a single piece of leather bifurcated in its sole portion and having on opposite sides thereof intermediate laterally projecting extensions or wings whose opposed edges extend along a medial line over and forward of the ball of the foot, the front edge of said front part being upturned and curved in substantially semi-circular form leaving an open space over the toes, and a toe-piece having a wide front portion adapted to cover said open space and having its front edge curved to conform to the curvature of said upturned edge of said front part and secured thereto by a substantially semi-circular seam, said toe-piece having a narrow tongue-like portion which extends from said wide front part rearwardly over the ball of the foot and overlies the opposed edges of said wings, said narrow portion being secured to said wings by seams on opposite sides of said medial lines, and rear upper and sole portions secured to said wings and to the sole portions of said front part, substantially as described.

2. In a moccasin, a front part or vamp and sole-piece made from a single piece of leather having its front edge curved in substantially semi-circular form and upturned around the toe portion and on both sides, and also having on opposite sides thereof intermediate its length laterally projecting wings which terminate rearwardly of said upturned toe portion and whose opposed edges extend along a medial line over and forward of the ball of the foot, so that an open space is left over the toes between said upturned toe-portion and the front edges of said wings, and a toe-piece having a wide front portion shaped to cover said open space and having its front edge curved to conform to the curvature of the upturned edge of said toe-portion and secured thereto by a substantially semi-circular seam, said toe-piece also having a long and narrow rearward extension which extends from said

wide front part rearwardly over the ball of the foot and overlies and is secured to said wings by seams which extend on opposite sides of said medial line.

- 5 3. A moccasin comprising a front part or vamp made from a blank consisting of a single piece of leather having a V-cut in its sole portion and having intermediate laterally projecting extensions or wings on opposite sides thereof which terminate in advance of the rear ends of the sole portions, the edges of said wings being straight, and the front edge of said vamp being continuously curved in approximately semi-circular form 10 from one wing to the other and upturned to leave an open space over the toes, the outer edges of the said sole portions being curved from the rear edges of said wings to their rear extremities, a toe-piece having a wide 15 front portion covering said open space, and the front edge of which is curved to con-

form to the curvature of said continuously curved front edge of said vamp, and a rearwardly extending narrow portion which extends from said wide front part rearwardly 25 over the ball of the foot and is connected to said wings by seams which extend on opposite sides of the medial line of the foot near said line, so as to leave a space between said edges along said medial line, the front 30 curved edges of said vamp and toe-piece being secured together by a substantially semi-circular seam, and rear upper and sole portions secured to said wings and sole portions of said front part, substantially as described.

In testimony whereof I affix my signature in the presence of two witnesses.
